26 Claims. (Cl. 179—171.5)

1

This invention relates to the amplitude modulation of carrier frequencies and is particularly concerned with wide band class B plate modulation of a radio frequency carrier using a reactance coupled modulator.

The invention includes a system for achieving wide band class B plate modulation of the final class C stage of a radio transmitter, and permits the use of over-all rectified inverse feed-back. With this system a large amount of inverse feed-back may be applied with essentially full effect over a band extending from approximately 20 to 50,000 cycles, with less than 1% distortion over the entire transmission band and with noise content of less magnitude than 60 db. below 100% modulation.

The many problems involved in the design of amplitude modulated transmitters capable of true high fidelity are familiar to persons skilled in the art. Generally, the most troublesome element in such a system is the modulation transformer, the inherent characteristics of which limit the system in most cases to uniform gain over a range of from about 20 to 10,000 cycles. Above approximately 10,000 cycles it is ordinarily mandatory that little if any over-all feed-back be permitted in order to avoid oscillation or "singing" at some higher frequency.

Various corrective methods have been proposed, the most commonly used being the application of audio frequency feed-back from the modulator plates back to some low level stage, with proper isolation means to remove the effects of the modulation transformer at the modulator plates. With this arrangement very effective distortion and noise reduction can be realized over the entire pass band at the output of the modulation transformer. These advantages cannot be fully utilized at the output of the transmitter, however, since the class C output circuit follows the output of the modulation transformer and therefore the full magnitude of distortion and noise arising in the class C system does not appear at the modulator plates; consequently it cannot be inversely fed back for cancellation.

The system just described, if augmented by rectified over-all inverse feed-back, is very effective in reducing relatively low frequency noise and distortion, but due to the fact that it involves the phase rotation and other effects inherent in the modulation transformer, it is necessary to render the over-all feed-back circuit inoperative above a very few thousand cycles, generally well within the pass band of the system. This means that high frequency distortion and

2

noise occurring within the class C equipment remain essentially uncorrected, making it virtually impossible to achieve high fidelity.

It has been demonstrated that certain types of audio transformers can be used in amplifiers incorporating large amounts of wide band feed-back provided provisions are incorporated to effectively remove the transformer from the circuit and by-pass it, at frequencies somewhat above the upper limit of the pass band, assuming of course that the transformer does not produce serious phase rotation within the pass band. Various methods are effective in so removing the transformer at these higher frequencies, but these only permit the isolation of double end to double end or single end to single end transformers. To date no effective method has been discovered for correcting that part of the circuit within the feed-back loop which incorporates the modulation transformer, which of necessity must be double end to single end, since no known isolating means will result in the desired amplifier operation at frequencies above which the transformer has been isolated. It has been shown (see Terman, Radio Engineering Handbook (1943), page 226) that such means to be effective, must be under accurate control as to frequency response, rate of attenuation, etc. for a range extending several octaves above the pass band.

Corrective proposals have been suggested in which two or even three modulation transformers, each differing in design for progressively increasing frequency bands, are selectively inserted into the system by appropriate networks in order to extend the range over which safe conditions of phase rotation and amplifier gain obtain. Such systems are unduly complex and involve so many difficulties that they are impractical.

I have discovered that it is possible to provide a system of the type described which eliminates the modulation transformer but which retains the high electrical efficiency required in the modulator output circuit and which is capable of proper frequency response and cut off conditions over a frequency band of several hundred thousand cycles. The provision of such a system constitutes one of the important objects of my invention.

The novel features that I consider characteristic of my invention are set forth in the appended claims; the invention, itself, however, both as to its organization and its method of operation, together with additional objects and advantages

thereof, will best be understood from the following description of a specific embodiment when read in conjunction with the accompanying drawings, in which—

Fig. 1 illustrates a circuit according to my invention, for wide band class B plate modulation, employing rectified radio frequency inverse feed-back; Figs. 2A to 2C illustrate oscilloscope traces of output wave forms under varying conditions, showing how I equalize the magnitudes of the positive and negative output waves of the respective output tubes shown in Fig. 1; Figs. 3A to 3C show the same wave forms shown in Figs. 2A to 2C when feed-back according to the present invention has been applied; Figs. 4A and 4B show the effect of improper adjustment of the phase control shown in Fig. 1; Figs. 5A and 5B show different forms of distortion that are commonly encountered in improper design of feed-back systems, said distortion being in the form of oscillation or "singing" on a 20 kc. wave; Fig. 6 shows frequency response, noise level and distortion curves; Fig. 7 illustrates a circuit for obtaining 100% modulation by returning the modulator and auxiliary driver cathodes to a negative low voltage supply.

Briefly describing the invention with reference to Fig. 1, modulator tube 15, operating as a class B amplifier (with its grid statically biased substantially to cut off), supplies negative half waves to the class C load, to which its output or anode circuit is directly connected as indicated by the arrow 39. Modulator 15 is fed with plate current through reactor 18 which also supplies current to the class C stage. Modulator 17 is similarly operated as a class B amplifier, but supplies positive half waves to the class C load through coupling condenser 20, the cathode of modulator 17 being grounded through reactor 19. Thus, I obtain double end (sometimes called "push-push") to single end operation without the conventional coupling transformer.

It should also be noted that the grid of modulator 15 is driven in conventional manner from driver 14, and the grid of modulator 17, which is highly degenerative, being a cathode follower, is driven from driver 16 which derives its plate supply from the A. C. output of the modulator stages at point 22. Thus, the plate supply at driver 16 is obtained from a voltage source which at the time modulator 17 is delivering its positive output wave, is actually higher than the voltage obtained from the high voltage supply E₂. In other words, tube 16, at the time modulator 17 is delivering its positive output wave, requires a higher plate voltage supply than can be derived from plate supply E₂ and it is therefore connected at 22 in order to obtain the additive effect of the modulator output and the voltage supply E₂. It is well known to those skilled in the art that the cathode of a cathode follower tube becomes more positive as its grid becomes more positive. In order to obtain a wide positive swing on the grid of tube 17, I connect the anode resistor of tube 16 to point 22, so that the effective plate potential of driver 16 is increased in a positive direction as the cathode of tube 17 goes positive. In this manner, I increase the positive swing on the grid of tube 17. Conversely, when tube 15 is delivering its negative output wave, capacitor 20, being connected between point 22 and the cathode of tube 17, applies a negative signal to the cathode of tube 17. This factor tends to render tube 17 conductive at a time when it should be non-conductive. However, tube 17 is held cut

off by the increased negative swing of driver 16 occasioned by the connection of its anode resistor to point 22. Viewed in another way, capacitor 20, resistor 21, capacitor 30 and resistor 32 constitute a regenerative network for applying to the control electrode of tube 17 the potentials between cathode and ground developed under dynamic operating conditions.

More specifically describing the invention with respect to the embodiment illustrated in Fig. 1, an audio input 10 is fed through an input transformer 11 and into the usual amplifying stages and circuits 12 and 13, only the first tube 12a of which is shown, to a driver tube 14 which drives modulator tube 15. A second modulator 17 is connected as a cathode follower and is driven by driver 16 whose grid is driven in phase with the grid of tube 15. Tube 16 is arranged as a phase inverter. Grid excitation of tube 16 need not be obtained from the output of tube 14 but may be derived from any appropriate source of proper phase relation and voltage magnitude. Tubes 14 and 16 constitute push-pull-output signal translating means for driving tubes 15 and 17. Grid bias is applied to the modulator grids from voltage supply E₁ through resistors 31 and 32 as shown and plate voltages are applied from voltage supply E₂. Air core reactors 18a and 19a are incorporated respectively in series with reactors 18 and 19 in order to obviate iron circuit losses, capacity effects or resonance effects at frequencies well above the pass band. Resistors may of course be used in place of these reactors if the inherent power losses can be tolerated.

The output of the modulators is taken off at terminal 21 and applied to the class C load at 39 in the form of modulated D. C. It is preferable that the class C load be connected directly to point 22 although it is possible to connect it indirectly by the use of suitable isolating means, in which case the plate voltage for the class C load might be supplied independently of E₂. Rectified R. F. is fed back from the class output in known manner through line 33 and anti-sing filter 34 to the grid of the first tube 12a, it being understood that the feed-back circuit is carried through the secondary 35 of transformer 11. A by-pass capacity 36 is provided for minimizing the phase rotation effects of the secondary winding 35. One or more anti-sing filters may of course be included in preliminary stages 12 or 13.

As previously indicated, the plate supply voltage of tube 16 is not obtained wholly from a steady D. C. source in the conventional manner, but instead is connected to the modulator output at 22. Thus, during the negative grid excursions of driver 16 its positive plate excursion is augmented by the dynamic positive excursion at point 22, thus producing a positive bias excursion at the modulator tube 17, actually in excess of the positive cathode excursion of modulator 17. This requirement is made necessary because tube 17 is highly degenerative and therefore requires a positive grid excursion with respect to ground which is substantially equal to its cathode excursion plus its grid bias. If desired, the plate voltage on tube 16 may be derived from a separate source of high voltage substantially in excess of E₂, but this would involve a sacrifice in utilizing the full benefits of the invention. Thus it will be seen that I have provided a cathode follower tube 17 having an un-bypassed reactive cathode impedance 19, 19a, an output reactor 18, 18a, a capacitor 20 for coupling said impedance to said output reactor, and a network 22, 21, 30, 32 for

regeneratively coupling said reactor to the input of said tube.

Resistor 43 is an equalizing resistor inserted in the cathode circuit of driver 16 in order to adjust the degeneration of the tube and equalize or balance the output waves appearing in the output circuits of modulators 15 and 17. It should be noted that the only bias applied to tube 16 is through resistor 43 in its cathode circuit. This resistor has an adjustable condenser 23 in shunt therewith for adjusting the phase relation of the output waves of tubes 15 and 17.

Resistor 25 is a grid return resistor for tube 16 to keep the grid circuit closed. Resistors 38 and 21 are plate circuit resistors conventionally used in resistance coupled amplifiers. Reactors may replace these resistors provided adequate anti-sing precautions are followed. Resistor 38a is a conventional screen grid resistor to insure proper voltage on the screen grid of driver 14. The circuit contains the usual blocking capacitors 28, 29 and 30, cathode by-pass capacitors 44, 45 and screen by-pass capacitor 46.

The constants of the circuit of Fig. 1 should be designed as far as practicable in accordance with television practice for wide band operation. The following components and values are illustrative of what may be used in the novel modulation system described.

The foregoing data were obtained from a low power set-up in which the principles and operation of the invention were embodied.

Figs. 2A, 2B and 2C represent oscilloscope traces of an output wave without feed-back for three conditions of adjustment of cathode resistance 43 of driver 16 showing how the amplitudes of the positive and negative waves may be equalized. In Figs. 2A and 2C the results of improper adjustment are shown. An excess bias was put on tubes 15 and 17 for the purpose of emphasizing the cross-over points.

Figs. 3A, 3B and 3C represent the same waves under identical conditions except with inverse feed-back according to the invention, showing how the effects shown in Figs. 2A to 2C are removed and a perfect wave form obtained, even with improper adjustment of control 43.

Figs. 4A and 4B show the form of output waves, without feed-back, when improper capacity values are used at condenser 23, the positive and negative half waves being slightly out of their correct phase relationship, thus producing a distorted wave.

Figs. 5 and 5A show typical distortion of the output waves with improper filter constants in

the feed-back or amplifier circuits, or both. In each figure a 20 kc. fundamental wave is shown; in Fig. 5A a very high frequency "sing" appears on the fundamental and in Fig. 5B a lower frequency is discernible on close inspection.

Frequency response curves A, with, and B, without, 35 db. feed-back, are shown in Fig. 6, showing uniform gain across a band of approximately 100 kc. with feed-back applied. Noise level was constant at about -68 db. and distortion was approximately constant at less than $\frac{1}{2}$ of 1% up to 10,000 cycles, which was the limit of the measuring equipment. The curves of Fig. 6 were obtained from data taken on the set up-described in detail above.

For 100% modulation it is necessary to operate the modulator tubes at a plate voltage higher than that used for the class C amplifiers. This can be accomplished by returning the ground end of the modulator circuit to a positive grounded low voltage rectifier. A circuit for this purpose is shown in Fig. 7, which is similar to Fig. 1 with the following exceptions.

Instead of connecting the cathodes of tubes 15 and 17 to ground they are returned to an intermediate tap —C' of the bias rectifier E₁, the full tap —C of which supplies bias to the modulator grids through a potential divider. 100% modulation is thus obtained at substantially the same rectifier power as required in a conventional circuit, since the increased demand from the low voltage or bias rectifier is of the same order of magnitude as the decreased demand from the main high voltage (plate) rectifier. This decrease is brought about by the improved modulator efficiencies at higher plate voltages and by the elimination of modulation transformer losses.

It will be noted that the cathode return of tube 16, shown grounded in Fig. 1, is now connected at point 41 with point 40 in order to effectively increase the plate voltage on tubes 15, 16 and 17. Thus, the voltage between the modulator plates and cathodes is increased by an amount substantially equal to that effected by the turns ratio of the modulation transformer that would otherwise have been necessary in order to achieve 100% modulation.

It will also be noted that 100% modulation may be obtained with the circuit of Fig. 1 either by operating the class C tubes on an additional rectifier of lower voltage than E₂, or by inserting a resistance in series with the load 39 and bypassing it for A.C. These measures, however, entail very considerable additional capital investment in high power equipment, lower efficiencies and concomitant higher operating costs.

Having thus described my invention, I claim:

1. A modulation system comprising an input voltage amplifier, a driver, a negative half cycle modulator, an output circuit for said modulator, a load, a conductive connection between said output circuit and said load, a second driver having a grid connected to the output of said first driver and consisting of a phase inverter, said second driver having its plate conductively connected to said output circuit, a positive half cycle modulator, having a cathode circuit, said second driver being connected to and driving said positive half cycle modulator, an inductive reactance in said cathode circuit across which the output voltage of said positive half-cycle modulator is developed, and a source of negative voltage, the cathodes of said modulators and said second driver being connected to said source for supplying cathode voltage to said modulators and said second driver,

said second driver having a cathode circuit including a resistance-capacity net-work for adjusting the amplitude and phase of the output of the positive half cycle modulator with respect to that of the negative half cycle modulator.

2. A modulation system comprising an input voltage amplifier, a driver, a modulator, an output circuit for said modulator, a load, a direct connection between said output circuit and said load, a second driver having a grid connected to the output of said first driver and consisting of a phase inverter, said second driver being connected directly to said output circuit, a second modulator, said second driver being connected to and driving said second modulator, said second modulator supplying half cycles of voltage to said load opposite in phase to those supplied by said first modulator, said second modulator having a cathode circuit, an inductive reactance in said cathode circuit across which its output voltage is developed, and a coupling capacity connecting the cathode of said second modulator to said load, the said output voltage being fed to said load through said capacity.

3. A modulation system comprising a first modulator, a second modulator, a load, a resistance coupled driver for said first modulator, said driver having a plate, said first modulator having its plate output directly connected to said load, said second modulator having a cathode circuit, an inductive reactance in said cathode circuit, across which an output voltage is developed, a capacitive reactance connecting said second modulator to said load for impressing said output voltage thereon, a second resistance coupled driver for said second modulator, said second driver having a grid, a connection between the plate of said first driver and the grid of said second driver, and connections between the output of said modulators for impressing a plate voltage on said second driver.

4. A modulation system comprising a first modulator, a second modulator, a load, a resistance coupled driver for said first modulator, said driver having a plate, said first modulator having its plate output directly connected to said load, said second modulator having a cathode circuit, an impedance in said cathode circuit, across which an output voltage is developed, a capacitive reactance connecting said second modulator to said load for impressing said output voltage thereon, a second resistance coupled driver for said second modulator, said second driver having a grid, a connection between the plate of said first driver and the grid of said second driver, and connections between the output of said modulators for impressing a plate voltage on said second driver, a source of negative voltage, and a connection thereto from the cathode returns of said modulators and said second driver.

5. In a modulation system, a driver, a modulator, an output circuit connected to said modulator and a load, a direct connection from said output circuit to said load, a second modulator, a second driver coupled thereto and a common source of plate voltage for said modulators and said second driver, whereby the said second driver has impressed thereon a plate voltage including all the A.C. components in the plate circuit of the output of said modulator.

6. In a modulation system, a driver, a modulator having an anode circuit, and a load, a direct connection from said anode circuit to said load, a second modulator having a cathode circuit, a second driver coupled to said second mod-

ulator, a common source of plate voltage for said modulators and said second driver and means for A.C. coupling said cathode circuit to the anode circuit of the first-mentioned modulator.

5. 7. In a modulation system, a negative half wave modulator, an output circuit connected to said modulator, and a load, a direct connection from said output circuit to said load, a positive half wave modulator and capacitive coupling means from said positive half wave modulator to said load.

10. 8. In a modulation system including an input voltage amplifier, a negative half wave modulator, an output circuit connected to said modulator, and a load, a direct connection from said output circuit to said load, a positive half wave modulator, capacitive coupling means from said positive half wave modulator to said load, and a feed-back connection from the output of said load to said input voltage amplifier.

15. 9. A modulation system comprising the combination of a first and a second modulator, drivers therefor for driving same, an output circuit for said modulators, and a load, a capacitively reactive coupling between the output circuit of the second modulator and said load, and a direct connection between the output circuit of the first modulator and said load.

20. 10. A modulation system comprising the combination of an input amplifier and a first and a second modulator, drivers therefor for driving said modulator, an output circuit for said modulators, and a load, a capacitively reactive coupling between the output circuit of the second modulator and said load, a direct connection between the output circuit of the first modulator and said load, and a feed-back connection between the output of said load and said input voltage amplifier.

25. 11. A modulation system comprising the combination of first and second half-wave modulators, an output circuit therefor, and a load, a capacitive coupling between the output of the second of said modulators and said load, and a direct connection between the first of said modulators and said load.

30. 12. A modulation system comprising the combination of opposite first and second half-way modulators, an output circuit therefor, and a load, a capacitive coupling between the output of the first of said modulators and said load, a direct connection between the output of the second of said modulators and said load, and a feed-back connection from the output of said load to the input of said system.

35. 13. A signal translating circuit comprising in combination with a load, means for producing positive and negative half wave output voltages, and means for applying the same to said load, the last mentioned means consisting of a direct connection from the output of the negative half wave voltage producing means, and a capacitive connection from the output of said positive half wave voltage producing means.

40. 14. A modulation circuit comprising in combination with a load, means for producing positive and negative half wave output voltages, and means for applying the same to said load, the last mentioned means consisting of a direct connection from the output of the negative half wave voltage producing means, a capacitive connection from the output of said positive half wave voltage producing means, and a feed-back connection from the output of said load to the input of said circuit.

15. A system for modulating a carrier wave comprising a pair of vacuum tubes for supplying a modulating voltage, means for supplying the negative half wave of said voltage from the plate of one of said tubes, and means for supplying the positive half-wave of said voltage from the cathode of the other of said tubes.

16. A system for modulating a carrier wave comprising a pair of vacuum tubes for supplying a modulating voltage, means comprising a conductive connection for supplying the negative half wave of said voltage from the plate of one of said tubes and means comprising a capacitive connection for supplying the positive half-wave of said voltage from the cathode of the other of said tubes.

17. In a plate modulation system, a class C amplifier having a plate circuit and a pair of vacuum tubes for supplying modulating voltages thereto, means comprising a direct connection from the plate of one of said tubes to said plate circuit for supplying thereto half of the modulating wave, and means comprising a capacitive connection from the cathode of the other of said tubes to said plate circuit for supplying thereto the opposite half of the modulating wave.

18. A signal network comprising a pair of electron tubes so arranged that the anode circuit of one of said tubes and the cathode circuit of the other of said tubes are coupled to a common output, and means for returning the cathodes of said tubes to a common point.

19. A signal network comprising a pair of vacuum tubes, one of which has an impedance in its anode circuit and the other of which has an impedance in its cathode circuit, said impedances being in D. C. parallelism, and common output circuit means for the alternating current signals developed in said impedances.

20. A signal network comprising a pair of vacuum tubes, an impedance in the anode circuit of one of said tubes between its anode and one terminal of a space current source common to both of said tubes, the junction of said impedance and said anode constituting an output terminal, another impedance in the cathode circuit of the other of said tubes between its cathode and the other terminal of said space current source, the junction of said impedance and said other terminal constituting the other output terminal, and means for coupling said other impedance to the first-mentioned output terminal.

21. The combination of a cathode follower having an impedance in its cathode circuit whereby its cathode tends to follow its grid and to develop a cathode bias of positive polarity in response to applied signals of positive polarity, a driver tube having an output circuit coupled to an input circuit of said cathode follower tube, a common space current source directly coupled to the anode of said cathode follower, a load including an A.-C. impedance for coupling said space current source to said driver tube anode, and means for increasing the anode potential of said driver tube comprising means for coupling the first mentioned impedance to the second mentioned or A.C. impedance whereby in response to A.C. signals of positive polarity applied to said input circuit, the A.C. signals developed across said first-mentioned impedance are applied to said anode in addition to the potential available from said source, thereby to increase the potential applied to the input circuit of said cathode follower over the potential which would be supplied by said driver when the

driver anode is supplied by said space current source only.

22. A signal network comprising a pair of vacuum tubes for supplying a voltage, coupling means for supplying a part of said voltage from the anode circuit of one of said tubes and coupling means for supplying another part of said voltage from the cathode circuit of the other of said tubes.

10 23. A modulator comprising a pair of class B arranged vacuum tubes for supplying a modulating voltage, the cathode and anode of one of said tubes being individually coupled to output terminals, means for supplying one half wave of said

15 voltage from the anode circuit of one of said tubes comprising a reactor in its anode circuit between one of said terminals and a space current source, means for supplying the other half wave of said voltage from the cathode circuit of the other of said tubes comprising a reactor in its cathode circuit between its cathode and the other of said terminals and a capacitor between its cathode and said one of said terminals, the anodes of both

20 of said tubes being coupled to a common space current source, whereby the modulating voltage and the potential from said space current source appear across said terminals.

24. A signal translating circuit adapted to be employed in conjunction with a common space

30 current source for modulating a radio frequency amplifier comprising the combination of a pair of vacuum tubes, one of which has an anode impedance and the other of which has a cathode impedance and means including a common output circuit for both of said impedances for coupling them to a load, the anodes of said tubes being coupled to a common space current source, whereby there appear across said output circuit the potential of said source and the output signals from

35 said tubes, and means for applying to the cathodes of both of said tubes a negative bias whereby the total effective potential impressed on the anode circuits of said tubes is greater than that appearing across said output terminals.

40 25. A modulating circuit comprising a pair of vacuum tubes and a pair of impedances arranged in a loop, one of said impedances being in the anode circuit of one of said tubes and the other of said impedances being in the cathode circuit of the other of said tubes, the cathode and anode of said one tube being connected to output terminals, and means for coupling said other impedance to the output terminal connected to the anode of said one tube.

45 26. A cathode follower tube having an un-by-passed reactive cathode impedance, an output reactor, a capacitor for coupling said impedance to said output reactor, and a network for regeneratively coupling said reactor to the input of said tube.
